UNITED STATES PATENT OFFICE.

ADOLPH MEYER AND WILLIAM A. GLOCK, OF ALBANY, NEW YORK.

CIRCUIT BREAKER.

Application filed June 8, 1922. Serial No. 566,843.

To all whom it may concern:

Be it known that we, ADOLPH MEYER and WILLIAM A. GLOCK, citizens of the United States, residing at Albany, county of Albany, and State of New York, have invented certain new and useful Improvements in Circuit Breakers, of which the following is a specification.

Reference may be had to the accompanying drawings, and the reference characters marked thereon, which form a part of this specification. Similar characters refer to similar parts in the several figures therein.

The principal object of the invention is to obtain a more perfect contact or engagement between the points of a circuit-breaker, and particularly of a circuit-breaker such as is used in the ignition systems of automobiles or the like.

Other objects will appear in connection with the following description.

Fig. 1 of the drawings is a top plan view of a circuit-breaker, the general construction of which is of a well known type used in automobile ignition systems, showing the contact-members mounted in accordance with my invention.

Fig. 2 is a similar view of a broken-away portion of the same on an enlarged scale and partly in cross-section.

Fig. 3 is a cross-section taken on the broken line 3—3 in Fig. 2 through the shank of the contact-member mounted upon the breaker-arm.

Fig. 4 is a cross section taken on the broken line 4—4 in Fig. 2, through one of the contact-points.

Referring to the drawings wherein the invention is shown in preferred form, 1 is the rotor of the circuit-breaker which operates in the usual manner, causing its cam-member, 2, to intermittently engage a cam-follower, 3, on the breaker-arm, 4, to cause separation of the contacts or breaker-points, 5 and 6.

The return movement of the breaker-arm, 4, whereby the contacts or breaker-points, 5 and 6 are brought together, is automatically caused by a spring, 7, in the usual manner.

The breaker-point, 6, is mounted upon the post or bracket, 8, while the breaker-point, 5, is mounted upon the breaker-arm, 4.

As shown in Fig. 2, the breaker-point, 5, is formed as part of a contact-member including a screw-threaded shank, 9, and a

spherical portion, 10, between the shank, 9, and the contact-point, 5.

The breaker-arm, 4, is formed with a spherical socket, 11, adapted to receive the spherical portion, 10, of the contact-member bearing the contact-point, 5, and provided with an aperture, 12, adapted to freely or loosely receive said screw-threaded shank, 9.

Fitting the screw-threaded shank, 9, is a nut, 13, adapted to engage a washer, 14, which in turn engages the breaker-arm, 4.

Between the nut, 13, and the washer, 14, I preferably interpose a spiral spring, 15.

The contact-member bearing the contact-point, 5, is thus rockably mounted upon the breaker-arm, 4, and can be adjusted by rocking the spherical portion, 10, within the socket, 11, to cause the contact-point, 5, to bear flatly against the cooperative contact-point, 6.

In setting up the mechanism, the nut, 13, is loosened to permit the contact-member bearing the contact-point, 5, to be rocked to bring its contact-surface flatly against the contact-surface of the neighboring contact-point, 6.

When the contact-member bearing the contact-point, 5, has been thus rockably adjusted, it is secured in fixed adjusted relation to the breaker-arm, 4, by setting up the nut, 13. I am thus able to readily make a flat contact between the contact-points, 5 and 6.

To further facilitate adjustment of the contact-points, we preferably form the contact-point, 6, as part of a contact-member, including a spherical portion, 16, and a screw-threaded shank 17, which spherical portion, 16, engages a spherical socket, 18, in the breaker-post or bracket, 8, which socket is provided with an aperture, 20, to freely receive the shank, 17.

Fitting the screw-threaded shank, 17, is a nut, 21, which engages the socket, 18, through the interposed coil-spring, 22, and washer, 23.

The contact-members bearing the contact-points, 5 and 6, can thus be rocked upon their respective supports to bring them into flat contact with each other, and then each contact-member may be locked in fixed relation to its respective supporting member.

One or both of the contact-points, 5 and 6, is preferably formed offset or eccentric to the axis of its supporting member, as shown in Fig. 4, whereby we are able by a rotative

movement of said contact-member about its axis to project its contact-point in any desired direction transversely of the axis of the contact-member.

5. Variations in vertical or horizontal position of a contact-point can thus be readily compensated for.

For certain purposes of the invention, one only of the contact-members may be rockably or eccentrically mounted in the manner above described.

The means for connecting the circuit-breaker in an electric circuit are not shown, as the same are well understood in the art.

15. What we claim as new and desire to secure by Letters Patent is—

1. In a circuit-breaker and in combination, a contact-member, and a supporting member, said members being formed with 20 cooperative spherical bearing-surfaces; means for securing said contact-member in selected angular position upon said supporting member, and rotary about its longitudinal axis, and having its contact-end offset 25 with respect to said axis; and means for securing said rotary contact-member against rotation; and a second contact-member, one of said contact-members being movable toward and from the other.

30. 2. In a circuit-breaker and in combination, a pair of contact-supporting members, one movable toward and from the other; a pair of contacts supported by the respective contact-supporting members, one of said 35 contacts and its supporting member having cooperative spherical bearing-surfaces, said contact-member being rotatory about its longitudinal axis and having an end contact-surface offset with respect to said axis; and 40 means for securing said contact in fixed an-

gular position rockably and rotatively with respect to its supporting member.

3. In a circuit-breaker and in combination a support formed with a spherical socket provided with an aperture; a contact-member having a contact-surface on one end, a rotatable screw-threaded shank on its other end projecting loosely through said socket aperture, said contact member being arranged eccentrically with respect to the axis of the shank, and an intermediate spherical portion rockably seated in said socket; a nut on the projecting end of said shank, whereby the contact-member can be secured in selected angular relation to its support and laterally displaced with respect to the axis of the contact member; and a second contact-member, one of said contact-members being movable toward and from the other.

4. In a circuit-breaker and in combination, a support formed with a spherical socket provided with an aperture; a contact-member having at one end a screw-threaded shank, projecting loosely through said aperture, at its other end a contact-surface eccentric with respect to said shank, and an intermediate spherical portion rockably seated in said socket; a nut on the projecting end of said shank, whereby the contact-member can be secured in selected angular relation to its support; and a second contact-member, one of said contact-members being movable toward and from the other.

In testimony whereof, we have hereunto set our hands this 3rd day of June, 1922.

ADOLPH MEYER,
WILLIAM A. GLOCK.
